CLAIM

The ornamental design of a bacon cooker, as shown and described.

DESCRIPTION

FIG. 1 is a perspective view of a bacon cooker, in accordance with the invention;

FIG. 2 is a front plan view thereof; the rear plan view being a mirror image thereof;

FIG. 3 is a right side elevation view thereof; the left side elevational view being a mirror image thereof;

FIG. 4 is a top plan view thereof; and,

FIG. 5 is a bottom plan view thereof in accordance with the invention.
